MECHANISM FOR AND METHOD OF PRODUCING RECEPTACLES

Harry L. Evans, Newport, R. I., assignor to United States Automatic Box Machinery Co., Inc., Roslindale, Mass., a corporation of Massachusetts.

Application January 17, 1939; Serial No. 251,375.

8 Claims. (Cl. 113—46)

This invention relates to mechanism and method for producing receptacles formed from sheet material.

The invention has for an object to provide a method of making receptacles of novel structure from sheet material, including the step whereby, preparatory to making up the receptacle, said sheet material is subjected to a preliminary shaping or preforming operation adapted to provide the desired hollow internal shape of the ultimate receptacle.

The invention has for a further object to provide a method of making receptacles from ductile sheet material comprising, stretching one or more portions of the area of the sheet material blank into fixed cavo-relievo form; then folding the sheet material so shaped upon itself, or otherwise superposing sections thereof; so as to provide by the cavo-relievo portion or portions a hollow receptacle interior of predetermined size and shape, and then joining meeting marginal portions of the thus folded or superposed material to provide closure seams or joints to complete the receptacle.

The invention also has for an object to provide novel means for stretching the desired areas of the receptacle material into performed cavo-relievo formations.

Other objects of this invention, not at this time more particularly enumerated, will be comprehended in the following detailed description of the same.

An illustrative embodiment of the novel receptacle according to this invention, as well as steps in the novel method of producing the same, are shown in the accompanying drawings, in which:

Fig. 1 is a schematic view illustrating certain steps in the method of producing the novel receptacle, certain of the mechanisms used in the performance of said steps being shown in section; Fig. 2 is a plan view of the sheet material as preformed to provide cavo-relievo portions preparatory to making up the receptacles; Fig. 3 is a top edge view of the preformed material as initially folded into receptacle form; Fig. 4 is a face view of the initially folded preformed material drawn on an enlarged scale; and Fig. 5 is a transverse sectional view of the same.

Fig. 6 is a face view of the folded preformed material, showing a seaming or jointing of the sides of the receptacle; and Fig. 7 is a transverse sectional view thereof.

Fig. 8 is a face view of the folded preformed material, showing an optional additional seaming.

or jointing of the receptacle sides; and Fig. 9 is a transverse sectional view thereof.

Fig. 10 is a face view of the receptacle showing a method of finally closing its open end or mouth; and Fig. 11 is a vertical longitudinal sectional view of the thus closed and completed receptacle.

Similar characters of reference are employed in the above-described views, to indicate corresponding parts.

The receptacle, according to this invention, is produced from ductile sheet material, that is, from a flexible material capable of being stretched into a predetermined desired form or shape, and also capable of being folded for desired disposition of the receptacle parts, and for seaming or joining the latter in receptacle-forming relation. One type of ductile sheet material, suitable for use in making up the receptacle pursuant to the novel method according to this invention, is a metallic foil, such as tin foil, aluminum foil or the like. Preferably the ductile sheet material is made up into a roll (not shown) of suitable width from which the same is drawn and thereupon preformed; the same being cut into lengths or blanks suitable for forming the ultimate receptacles, either before or after preforming thereof. The operations of feeding the sheet material, preforming the same, and then manipulating it to form the ultimate receptacles may be carried on continuously by suitable mechanical agencies if desired.

According to the method of this invention, the sheet material blank is subjected to preliminary preforming operation whereby desired areas thereof are stretched and drawn out, by force applied perpendicular to the plane thereof, so as to produce fixed cavo-relievo sections located within and intermediate its marginal limits, which, when the open sides thereof are closed over by cooperating superposed sections of material, provide a receptacle having a hollow interior of predetermined size and shape.

One way of applying preforming force to the sheet material, which is illustrative of the principle of this step of the novel method according to this invention, is to clamp the outlying marginal areas of the sheet material blank against movement and so as to dispose and hold the interior area or areas desired to be preformed between and subject to the cooperative action of male and female stretching and forming means. In Fig. 1 of the drawings a means of such character is shown, the same being arranged to stretchingly preform spaced areas within a blank forming length of the sheet material, to

thereby produce longitudinally spaced and aligned opposable cavo-relievo sections adapted to be brought into registered opposed relation by subsequently folding the blank upon itself, whereby said opposed cavo-relievo sections define the desired predetermined hollow interior of the ultimate receptacle. As shown in said Fig. 1, the preforming means comprises a stationary frame or block 1 having in its under face longitudinally spaced cavities 2 of peripheral shape adapted to define the peripheral limits and outline shape desired to be given to preformed sections or areas of the receptacle blank. The portions of the frame or block 1 which skirt said cavities provide clamp sections 3 to engage the top faces of the sheet material blank marginal to the areas thereof to be preformed. Vertically movable on supporting rods 4, dependent from said stationary frame or block 1, is a combined movable clamp and female stretcher block 5, which is yieldably urged by compression springs 6 toward said stationary frame or block 1. Said block 5 is provided in its top face with longitudinally spaced cavities 7 constituting female stretcher means. Said cavities 7 correspond in peripheral shape to the peripheral shapes of the stationary frame or block cavities 2, and thus also to the peripheral limits and outline shape desired to be given to the preformed sections or areas of the receptacle blank. The portions of said clamp and stretcher block 5 which skirt its said cavities 7 provide clamp sections 8 to engage the bottom faces of the sheet material blank marginal to the areas thereof to be preformed; thus being cooperative, at proper times, with the clamp sections 3 of said stationary frame or block 1. The operation of said block 5 may be controlled by a rotatable cam 9 fixed on a drive shaft 10. Said block 5 is provided with dependent slotted arms 11 through which shaft 10 extends, and in connection with the free ends of which is carried a roller 12 cooperative with said cam 9. Provided in connection with said stationary frame or block 1, perpendicular to the cavities 2, are guideway means 13 to slidably support plunger rods 14, upon the lower ends of which are affixed male stretcher members 15. Said stretcher members 15 respectively lie within the cavities 2, and, while substantially conforming in peripheral shape to the peripheral shape of said cavities 2 and of the cavities 7 of the clamp and stretcher block 5, are of less all over dimension so as to provide material stretching clearance intermediate the peripheries thereof and the peripheries of said cavities 7 of the clamp and stretcher block 5. Said plunger rods 14 are affixed by their upper end portions to a cross head 15. Said cross head 16 is slidably supported on upstanding supporting rods 17 carried by said stationary frame or block 1, and is yieldably urged downwardly by compression springs 18 which, when free to act, serve to thrust said male stretcher members 15 into operative relation to the material blank desired to be stretchingly preformed. Such operation of said male stretcher members 15 may be controlled by rotatable cams 19 mounted on and actuated by said drive shaft 10, which cams, to this end, cooperate with rollers 20 carried by arms 21 dependent from said cross-head 16.

When, by operation of the cams 9 and 19 respectively, the combined clamp and female stretcher block 5 is lowered against the tension

of the springs 6, the male stretcher members 15 are raised against the tension of the springs 18, the sheet material F is, by the action of feed rolls 22-23, drawn from the source of supply and advanced between the stationary frame or block 1 and the lowered clamp and female stretcher block 5, and then stopped subject to the action of the male and female stretcher means. Preparatory to the stretching and preforming operation of said male and female stretcher means, the cam 9 first releases the block 5 for upward movement under the thrust of the springs 6, thereby engaging the longitudinal side areas M and transverse areas M' of the material F (which are marginal to the areas desired to be stretched and preformed) between the closed together clamp sections 3 and 8, thus gripping and holding such marginal areas against both bodily shift and stretch. When the material is thus gripped, the cam 19 operates to release the male stretcher members 15 for downward movement under the thrust of the springs 18. The downward thrust of said male stretcher members 15 engages the bottom faces thereof with underlying portions of the material F freely extending intermediate the cavities 3 and 7, thereby carrying the same downward into engagement with the bottoms of the cavities 7, and thus stretching those portions of the material extending across the clearance spaces between the peripheries of said cavities 7 and the peripheries of said male stretcher members 15, whereby angular walls W are formed to define and fix the desired preformed cavo-relievo sections C offset from the plane of the material F.

Upon completion of the preformed cavo-relievo sections C, the male stretcher members 15 and the combined clamp and female stretcher block 5 are retracted by the respective cams 19 and 9 to normal initial inactive positions, whereupon the material F is fed along to remove the preformed blank from the preforming means, and to deliver to the latter a succeeding portion of the material F for like treatment.

It is desirable, when preforming a blank of the material F with opposable preformed cavo-relievo sections C, to provide at the same time means for scoring the transverse areas M' intermediate said sections to provide a preformed score S for facilitating the folding of the preformed blank upon itself so as to register the cavo-relievo sections C thereof in opposed relation.

As shown in Fig. 1, suitable shear means 24 is provided for severing a preformed blank from the run of the material F preparatory to folding the blank and thereafter completing the receptacle forming operations.

The severed preformed blank is delivered to folding means comprising suitable opposed folder guide elements 25 and a cooperating reciprocable folder blade 26. The preformed blank is delivered onto the folder guide elements 25 and beneath the initially raised folder blade 26, with its preformed score S aligned beneath the latter. When the preformed blank is thus positioned, the folder blade 26 is caused to descend, thus carrying the blank downward between the opposed downwardly curved ends 27 of the guide elements 25, thereby folding the blank upon itself so as to register the open faces of the cavo-relievo sections C in opposition, and at the same time bringing the flat marginal areas M and M' of the blank into meeting relation (see Figs. 3, 4 and 5). The opposed cavo-relievo sections C,

when thus brought together, establish an interior chamber of desired predetermined shape and capacity.

In a simple form of receptacle, the meeting flat marginal areas M may be merely adhesively secured together. To provide more rugged side closing joints or seams for the receptacle, especially when a receptacle of liquid and gas proof characteristics is desired, the meeting flat marginal areas M are doubled or folded back upon themselves to provide overlapping side closure seams or joints J, as shown in Figs. 6 and 7. Such seams or joints may be formed by a single overlapping fold, as in the case of said seams or joints J shown in Figs. 6 and 7; or the same may be formed by a plurality of successively overlapped folds, as in the case of the seams or joints J' shown in Figs. 8 and 9. If desired, the laps of the seam or joint folds may be additionally adhered by any suitable means of adhesion or adhesive agent, to thereby further assure the seal and strength of the seams or joints.

The novel receptacle produced by the method procedure above described, may be filled with a desired content through its open top end, which may easily be spread open for such purpose. After the receptacle is filled said top end may be closed in any suitable manner, but preferably by an overlapped fold seam or joint J'', similar in kind to the side seams or joints above described.

While the method procedure above set forth contemplates the provision, in a foldable blank of ductile material, of spaced preformed cavo-relievo sections C adapted to be brought together in opposed relation by folding the blank upon itself, it will be understood that, if desired, the blank may be preformed to provide but a single cavo-relievo section C, the open side of which may be closed to form the receptacle interior by folding thereover the remaining flat or non-preformed section of the blank. It will also be understood, that the receptacle may be made by preforming separate non-foldable blank sections of the sheet material, and thereafter superposing and joining the same to form the ultimate receptacle.

I am aware that many changes could be made in the steps of the method procedure and in the detail construction of the resultant receptacle, and that many apparently widely different embodiments of the features of this invention could be made without departing from the scope thereof as defined by the following claims. It is therefore intended that all matter contained in the above description or shown in the accompanying drawings shall be interpreted as illustrative and not in a limiting sense.

I claim:

1. In a method of making receptacles from ductile sheet material, the steps of clamping portions of a blank composed of such material which are marginal to an included area of an end portion thereof desired to be preformed, applying force perpendicularly to a central portion of said included area which is of reduced area as compared with the total included area to thereby depress said central portion and stretch the free portions of said included area which lie outwardly of said central portion thereof whereby to preform a fixed cavo-relievo section adapted to define and bound the interior space of the ultimate receptacle, then folding the other end portion of said blank over said first mentioned end portion thereof to thereby

close the open side of said cavo-relievo section, and thereafter joining the meeting marginal parts of said folded together end portions to complete the receptacle.

5. 2. In a method of making receptacles from ductile sheet material, the steps of clamping portions of a blank composed of such material which are marginal to two spaced apart included areas thereof to be preformed, then separately applying force perpendicularly to central portions of said included areas which are of reduced areas as compared with the total included areas to thereby depress said central portions and stretch free out portions of said respective included areas which lie outwardly of said central portions thereof whereby to preform said areas into cavo-relievo sections; then transversely folding the blank so preformed centrally through the flat section intermediate said cavo-relievo sections to bring the hollow interiors of the latter into opposed closed together relation and the outlying flat marginal portions into meeting relation, and thereafter joining said meeting marginal portions to complete the receptacle.

3. In a method of making receptacles from ductile sheet material, the steps of clamping portions of a blank composed of such material which are marginal to two spaced apart included areas thereof to be preformed, then separately applying force perpendicularly to central portions of said included areas which are of reduced areas as compared with the total included areas to thereby depress said central portion and stretch free portions of said respective included areas which lie outwardly of said central portions thereof whereby to preform said areas into cavo-relievo sections, then transversely folding the blank so preformed centrally through the flat section intermediate said cavo-relievo sections to bring the hollow interiors of the latter into opposed closed together relation and the outlying flat marginal portions into meeting relation, and thereafter folding said meeting marginal portions in doubled back relation upon themselves to form closure seams to complete the receptacle.

4. A method of making receptacles comprising advancing from a supply source a web of ductile sheet material to successively provide lengths thereof from which the receptacles are to be formed, clamping portions of an advanced length of said material which are marginal to two spaced apart included areas thereof to be preformed, then applying force perpendicularly to central portions of said included areas which are of reduced area as compared with the total included areas to preform each said included area by a stretching action applied to parts thereof which lie outwardly of said central portions thereof into a fixed cavo-relievo section, then further advancing the length of thus preformed material to another position and thereupon severing the same from the web, then transversely folding the severed length of preformed material centrally between the cavo-relievo sections to thereby bring the hollow interiors of the latter into opposed closed together relation and the surrounding flat marginal portions into meeting relation, and thereafter joining said meeting marginal portions to complete the receptacle.

5. A method of making receptacles comprising advancing from a supply source a web of ductile sheet material to successively provide lengths thereof from which the receptacles are to be formed, clamping portions of an advanced length of said material which are marginal to two

spaced apart included areas thereof to be preformed, then applying force perpendicularly to central portions of said included areas which are of reduced area as compared with the total included areas to preform each said included area by a stretching action applied to parts thereof which lie outwardly of said central portions thereof into a fixed cavo-relievo section, then further advancing the length of thus preformed material to another position and thereupon severing the same from the web, then transversely folding the severed length of preformed material centrally between the cavo-relievo sections to thereby bring the hollow interiors of the latter into opposed closed together relation and the surrounding flat marginal portions into meeting relation, and thereafter folding said meeting marginal portions in doubled back relation upon themselves to form closure seams to complete the receptacle.

6. In mechanism for preforming ductile sheet material for the production of receptacles therefrom, a stationary block, a cooperating spring pressed female stretcher block, said blocks having opposed cavities therein of peripheral shape and dimensions corresponding to an area of material to be preformed, said blocks having meeting portions surrounding their cavities adapted to clamp therebetween the interposed sheet material at areas thereof marginal to the area to be preformed, a spring pressed male stretcher device within the cavity of the stationary block and mounted for reciprocation in connection with the latter and in opposition to the cavity of said female stretcher block, said male stretcher device corresponding in peripheral shape to the peripheral shape of said female stretcher block cavity but being of less areal dimension whereby, in operation, to stretch portions of material being preformed which extend between the margins of said stretcher block cavity and the margins of said male stretcher device, means to control the spring actuated movement of said stretcher block into meeting relation to said stationary block, and additional

means to thereupon control the spring actuated movement of said male stretcher device for preforming effect upon the interposed sheet material

7. In mechanism for preforming ductile sheet material for the production of receptacles therefrom, a stationary block, a cooperating spring pressed female stretcher block, said blocks each having a pair of spaced apart cavities therein of peripheral shape and dimensions corresponding to spaced areas of material to be preformed, the cavities of said blocks being opposed, said blocks having meeting portions surrounding their cavities adapted to clamp therebetween the interposed sheet material at areas thereof marginal to the areas to be preformed, a pair of spring pressed male stretcher devices respectively disposed within the cavities of said stationary block and mounted for reciprocation in connection with the latter and in opposition respectively to the respective cavities of said female stretcher block, said male stretcher devices corresponding in peripheral shape to the peripheral shapes of the opposed cavities of said stationary and female stretcher blocks but being of less areal dimensions whereby, in operation, to stretch portions of material being preformed which extend between the margins of said stretcher block cavities and the margins of the male stretcher devices cooperative therewith, driven cam means to control the spring actuated movement of said stretcher block into meeting relation to said stationary block and additional driven cam means to thereupon control the spring actuated movements of said male stretcher devices for preforming effect upon the interposed sheet material.

8. In mechanism for preforming ductile sheet material for the production of receptacles therefrom as defined in claim 7, wherein said stationary female stretcher blocks have cooperative means between the spaced apart cavities thereof adapted to form a transverse fold score intermediate the areas of the interposed sheet material to be preformed.
